[57] CLAIM

The ornamental design for a shoe outsole, as shown and described.

DESCRIPTION

FIG. 1 is a left side elevational view of a shoe outsole showing our new design;

FIG. 2 is a right side elevational view thereof;

FIG. 3 is a front elevational view thereof;

FIG. 4 is a rear elevational view thereof; and,

FIG. 5 is a bottom plan view thereof.

The broken line showing of a shoe upper in FIGS. 1-5 and the area within is environmental only and forms no part of the claimed design.

FIG. 1

FIG. 2

FIG. 3

FIG. 4

FIG. 5
